UNITED STATES PATENT OFFICE.

LUDWIG MARSHALL, OF BROOKLYN, NEW YORK.

AEROPLANE.

Application filed June 25, 1926. Serial No. 118,529.

The present invention is concerned with the provision of a novel type of safety device for aeroplanes which acts to automatically restore the aeroplane to gliding position, either when it takes a nose dive, or when it slips backwardly.

Certain features of the invention are improvements on the type of aeroplane disclosed in my copending application Serial No. 71,168 filed November 24, 1925. The device of the prior application however, was subject to certain defects which I have remedied.

In the first place the old type of safety device detracted materially from the speed of a plane, and was therefore found unsuitable for use on fast planes. The device of the present invention does not retard the speed of the plane inasmuch as it presents no new air impingement surfaces, and is of extremely light weight.

The device of the prior application also depended for its operation upon the engine of the aeroplane, being adapted to act only when the engine stalled or was running at a dangerously slow speed. The device of the present invention acts altogether independently of the engine, and is operative to restore the plane to a glide either from a nose dive or a back slip regardless of the condition of the engine.

The invention in its preferred embodiment contemplates the use of a safety rudder acting automatically to restore the aeroplane to a gliding position. The movement of the safety rudder is so correlated with the movement of the tail rudder that the action of the machine will be substantially automatic. When the plane dives the tail rudder coacts with the safety rudder to swing the nose of the plane upwardly, and when the plane reaches horizontal position, the tail rudder opposes the action of the safety rudder to prevent the plane from making a complete loop. In other words, the nose of the plane swings upwardly, bringing the plane into horizontal position, and the tail rudder thus acts to retain the plane in such position, or to throw it into a glide.

Other objects of the invention are to provide an automatically acting safety device on the aeroplane, of simple, practical construction, which will be rugged, durable and efficient in use, capable of manufacture with comparative economy, and capable of

being readily applied to an ordinary type of plane.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a view partly in side elevation and partly in longitudinal section of an aeroplane embodying the present invention, two additional positions of the safety rudder and tail rudder being indicated in dotted lines.

Fig. 2 is a side elevational detail looking at the opposite side of the aeroplane from Fig. 1, and showing the safety rudder in its vertical position with the other two positions thereof indicated in dotted lines.

Figs. 3 and 4 are side elevational views of the tail rudder control levers viewed from the opposite side of a plane, to that shown in Fig. 1. In Fig. 3 the levers are thrown to swing the tail rudder into climbing position, the normal position of the levers being indicated in dotted lines. In Fig. 4 the normal position of the levers is shown in full lines, and the position of the levers to throw the tail rudder into climbing position is shown in dotted lines.

Fig. 5 is a somewhat diagrammatic perspective view of the aeroplane showing the position of the parts, when the plane is taking a nose dive, in which it will be seen that the safety rudder is swung to vertical position and the tail rudder to climbing position.

Fig. 6 is another perspective view showing the position of the parts when the plane has been restored to horizontal position by the action of the safety rudder and tail rudder. Here it will be noted that the tail rudder is swung to gliding position to prevent further rise of the nose of the plane.

Fig. 7 is another perspective view showing the position of the parts when the plane is back slipping.

Fig. 8 is a side elevational view of the safety rudder in normal position.

Fig. 9 is a view thereof after the same has been moved to vertical position and after the swinging section has been released.

Fig. 10 is a perspective view of the safety

rudder showing the position of the parts just before movement of the rudder proper is initiated at the time of the nose dive.

I have elected to show the invention as applied to a monoplane, but it is to be understood at the outset that the safety device may be attached with equal facility to a biplane or other types of heavier than air craft. The body of the plane is indicated at 10, the usual vertical tail rudder at 11, horizontal rudder at 12, and movable flaps of the horizontal rudder at 13. Immediately behind the cockpit 14 of the plane there is a depression 15 in the top of the body between the wings 16. This depression is located just behind a rail 17 in the body, and when the safety rudder is in its normal position, it will be screened from the action of the wind by the rail 17, whereby no additional air resistance is offered by the safety wing.

The construction of the safety wing itself may be best seen from Figs. 8 to 10 inclusive, in which it will be noted that the wing includes a swinging frame consisting of a pair 25 of arms 19 connected at one end by a cross shaft 20 which serves as a pivot for the frame. Shaft 20 is journalled in suitable bearings in the top of the aeroplane body and is acted upon by coiled torsional springs 30 21 to retain the frame 19 in the horizontal position illustrated in Fig. 8. A generally rectangular frame 22 is pivoted near one end between the free ends of the arms 19, this pivot point being indicated by the reference numeral 23. The larger portion of the frame 22 extends rearwardly from the pivots 23 in Fig. 8 and the smaller portion thereof extends forwardly from the pivots. A cross shaft 24 carried by the forward end of the frame 22 serves as a pivotal mounting for a flap 25, upward swinging movement of which is limited by fingers 26 projecting inwardly from the frame 22. The flange 26 which overlies the forward end of the frame 45 22 is ordinarily latched in position by a gravity latch 27 best seen in Fig. 8. This latch is acted upon by a spring 28 and includes a keeper portion 29 normally overlying the flap 25. When however, the aeroplane dives at a dangerous angle, the latch 50 27 will overcome the spring 28 and will swing forwardly, releasing the flap and the forward end of the frame 22. Frame 22 is covered with canvas or other suitable material 30 to form the safety rudder proper, and the flap 25 is designed to initiate upward swinging movement of the safety rudder to the vertical position shown in Fig. 5.

In order to initiate upward movement of 60 the flap after the gravity latch has been released, I provide a pair of cylinders 30^a which may either be mounted in the body of the aeroplane or secured to the frame 22. Operating pistons 31 connected to the flap 65 25 near its hinged edge are adapted to be

engaged by balls 32 rolling in the cylinders. Thus, as the plane dives forwardly, the gravity latch swings out of operative position, and the balls 32 rolling in the cylinders will kick the flap to the position shown in Fig. 70 10 and in dotted lines in Fig. 8. As the flap is raised, the wind has a chance to get under it, and pick the entire swinging frame 19 up bodily, swinging this frame with its associated rudder 30 to the vertical position 75 of Fig. 5, where it is stopped by any suitable means, such for instance as the stop brackets 33 secured to the body.

As the safety rudder swings to the vertical position of Fig. 5, it will offer enough air resistance to restore the plane to horizontal position and in this, restoration will be assisted by the tail rudder 13 in a manner to be later described.

When the safety rudder swings to the vertical position of Fig. 5, it will be noted that the portion thereof below the hinge 23 offers considerably more area to the wind than does the portion above this hinge. Swinging movement of the frame 22 on the hinge 23 is prevented however, by the presence of a cross bar 35 carried by the lower ends of arms 36 which in turn are pivotally connected at 37 to arms 38 pivoted at 39 to the frame bars 19. Extensions of the arms 38 are counter-weighted at 40 and the lower ends of the arms 36 are provided with eyes or similar devices 41 which afford a sliding connection on the lower or rear ends of the frames 19. The counter-weighted arms are so arranged that when the safety rudder is in the position of Fig. 8, the arms will hold the cross bar 35 in position to prevent rearward swinging movement of the rudder 30. When the rudder is in the vertical position 105 of Fig. 5 however, and the plane gradually rights itself and is restored to horizontal position, the counter-weights 40 will cause the arms 38 to swing rearwardly to the position of Fig. 9, thereby sliding the cross arm 110 35 downwardly, so that it will clear the lower end of the rudder 30. At this time, differential air pressures on the rudder will swing the latter to the horizontal position 115 of Fig. 6, and the rudder will cease to function. Inasmuch as the rudder offers no appreciable air resistance in the position of Fig. 6, the frame 19 and its associated mechanism will immediately be restored to its normal inoperative horizontal position by the springs 120 21.

As the rudder swings back to the position of Fig. 8, it will automatically latch itself by the gravity latches 27, acting on the cam surfaces 45 of these latches to force the latches forwardly as it swings into position, after which the spring 28 will reset the latch. It may be noted, that the flap 25 is automatically rendered inoperative by associated coiled expansion springs 46 as soon as the 130

safety rudder reaches the vertical position of Fig. 5, and that the latching bar 35 is automatically restored to inoperative position by the counter-weights 40 as the frame 19, 19 and its associated rudder is restored to horizontal position. In Fig. 6 I have indicated the rudder 30 just released by its latching bar 35 and swung to horizontal position. Immediately after it reaches this position, it will be restored to the inoperative position of Fig. 8 and Fig. 1. At the same time that the rudder 30 swings to the position of Fig. 6 it acts to automatically control the tail rudder 13, swinging the latter downwardly into the gliding position illustrated in Fig. 6. Thus, as the nose of the plane is swung sharply upwardly by the combined action of the safety rudder and tail rudder in Fig. 5, the position of the tail rudder will be reversed in time to prevent the plane from making a complete loop and from swinging its nose too far upwardly.

The action of the springs 21 which restore the frame 19 and its associated rudder to inoperative position may be aided if necessary or desirable by the action of counter-weights 24 secured to the shaft 30. These counter-weights are desirable because they offer one convenient attachment for the operating connections between the frame 19 and the tail rudder which will be later described.

Pivotedally connected to the cross shaft 24 is a flap 49 normally overlying the main body portion of the rudder 30. This flap becomes active in the event that the plane back-slips, as shown in Fig. 7. The flap is operatively connected to a pair of counter-weights 50 which serve to initiate movement of the flap when the plane reaches a dangerous angle with its nose too high above its tail. Thus, if we assume that the frame 19 and all of its associated mechanism is in the normal position of Fig. 8, and the plane starts to backslip, the counter-weights 50 will become operative as soon as the plane reaches a dangerous angle, serving to slightly lift the free edge of the flap 49 and permitting the wind to get under the flap and raise it to the position of Fig. 7. As the flap reaches the position of Fig. 7, further movement thereof is limited by the fingers 26 and the flap will act to restore the plane to horizontal position, as will be readily understood. When the plane again goes forwardly, the wind pressure on the forward face of the flap 49 will automatically swing it back to inoperative position.

I have thus far described the action of the safety rudder on a nose dive, and the action of the flap 49 on a back slip. I shall now explain the manner in which movement of the safety rudder is automatically correlated with the movement of the tail rudder, so that the tail rudder assists the safety rudder

from a nose dive to horizontal position, and prevents the plane from making a loop after it has been reset to either climbing or normal flying position after the safety rudder has performed its function and been restored to normal position.

The tail rudder control mechanism may be best seen from Figs. 2, 3 and 4, and is adapted to act on the main control lever 60 of the plane.

This control lever is pivoted at 61 and the controlling cables 62, 63 for the rudder 13 are connected to the lever 60 above and below the pivot respectively. The rear ends of these cables connect with crank arms 64, 65 rigid with the rudder 13, so that forward movement of the lever 60 will tend to elevate the rudder, causing the plane to climb, and rearward movement will tend to lower the same, causing the plane to glide. With the lever in its normal position shown in full lines in Fig. 4, the rudder 13 will be in an approximately horizontal position. Automatic control mechanism for this rudder in no way interferes with the normal manual operation of the lever 60, but is adapted to shift this lever to either forward or rearward position in case of an emergency without requiring any manual manipulation thereof.

A pair of automatic control levers 66, 67 are crossed and pivoted on the shaft 61, the upper ends of these levers being adapted to engage one side or the other of the control lever 60, in the event that the levers 66 or 67 are locked on their pivots. A spring 68 connects the lower ends of the levers 66, 67 and tends to draw these ends toward each other. The levers are normally held apart against the action of the spring by a pair of latches 69 connected to cables 70 which run over suitable pulleys 71 and are connected to part of the frame 19. As illustrated, these latches are directly connected to an eye 72 on the arm which carries the counter-weight 48. Thus, as the frame 19 moves upwardly from the full line toward the dotted line position of Fig. 1, cable 70 will be pulled to disengage the latches 69 and permit spring 68 to act upon the levers 67 and 66, drawing them together.

The pivot shaft 61 of the levers 60, 66 and 67 is preferably mounted between a pair of upstanding brackets 73. A disc 74 eccentrically mounted on one of the brackets 73 is rotatable about its eccentric pivot 75, and is acted upon by a coiled spring 71 anchored to the bracket 73. Disc 74 is connected to the lever 67 by a belt or other suitable connection 77, so that as the disc is swung from the full line to the dotted line position of Fig. 4, it will carry with it the lever 67. The disc is ordinarily held in the position of Fig. 4 against the action of its spring by a latch 78 pivoted to the

bracket 73, this latch being spring pressed into disengaging position by a coiled expansion spring 79.

When the latches 69 are disengaged, the disc serves to determine the relative positions to which the levers 66 and 67 are shifted by their springs 68. With the disc in the position of Fig. 4, releasing the latches 69, will cause the levers 66 and 67 to be 10 swung to the dotted line position of Fig. 4, in which position it will be noted that the free end of lever 66 has forced the control lever forwardly and consequently has lifted the tail rudder 13. In Fig. 4, I have shown the position of the parts after latch 78 has been released and permitted the spring 76 to shift the disc 74 to its opposite extreme position. In this position it will be 20 noted that the levers 66 and 67 are drawn inwardly by the spring 78 against the disc 74 and that the upper end of the lever 67 has moved the control lever 60 rearwardly, swinging the tail rudder downwardly and throwing the plane into gliding position.

25 To effect disengagement of the latch 78 from the disc 74, I connect this latch through the intermediacy of a cable 80 run over pulleys 81 to the frame 22. Thus, when the frame swings from the vertical dotted line position indicated in Fig. 1 to the horizontal dotted line position, cable 80 will be pulled to retract the latch 78 and permit the disc 74 to be shifted to the dotted line position of Fig. 4.

30 Means is also provided for automatically restoring the lever 60 to its central or neutral position even though the levers 66 and 67 are unlatched, and without requiring manual operation of the lever 60. To accomplish 35 this result, I connect lever 66 by a slot and pin connection 82 to an arm 83 drawn rearwardly by a coiled contractile spring 84. Rearward shifting movement of the arm 83 under the influence of spring 84 is normally 40 prevented by a spring latch 85 which engages the arm. This latch is connected to a cable 86 anchored to one end of a bell-crank lever 87 disposed in the path of movement of the counter-weight 48. The spring 45 84 is stronger than the spring 71, so that if we assume the latches 69 to be disengaged, and the disc 74 swung to the full line position of Fig. 3 by the action of its spring, release of the latch 85 will permit the spring 50 84 to balance or counteract the spring 71, and consequently shift levers 66 and 67 to bring the levers 60 to their neutral central 55 position.

60 Having thus described the general construction of the automatic control lever system, I may briefly outline its operation in connection with the movements of the safety rudder.

65 Assume that the parts are in the full line position of Fig. 1, with both levers 66 and

67 latched, with the latch 78 engaging the disc 74 and with the latch 85 out of engagement with the arm 83. As the supplemental safety wing swings to, toward the vertical position shown in Fig. 5, the counter-weight 48 will first move off of the bell crank 87 and permit the latch 85 to operate and engage the arm 83. Upon further movement of the safety rudder to vertical position, the arm of the counter-weight 48 70 will have taken up the slack in cables 70 and will retract the latches. Levers 66 and 75 67 will spring to the dotted line position of Fig. 4, shifting the control lever 60 forwardly and swinging the wing 13 up to 80 climbing position. At this time the parts are in the position shown in Fig. 5, with both the safety rudder and the tail rudder tending to restore the plane to normal position.

85 As soon as the plane has been righted sufficiently to permit the counter-weights 40 to act, and release the rudder 30, this rudder will swing to horizontal position, and as it does so, will pull upon the cable 80 to 90 retract the latch 78. It is to be borne in mind, that at this time the arm 83 is still latched, and unlatching the disc 74 will simply permit the spring 71 to act and shift the disc 74 to the dotted line position 95 of Fig. 4, which is the full line position of Fig. 3. When this occurs, the relative positions of the levers 66 and 67 will again be shifted to an extent determined by the position of the disc 74, and the control 100 lever 60 will be pulled rearwardly, throwing the tail rudder 13 downwardly into gliding position. By virtue of this arrangement, any tendency of the nose of the plane to continue swinging up after 105 horizontal position is reached, is successfully counteracted, and there is no danger of the plane looping the loop. With the levers in the full line position of Fig. 3, the relative position of the tail rudder and safety 110 rudder is shown in Fig. 6. In this figure, it will be noted that the tail rudder 13 is swung downwardly to gliding position and the safety rudder 30 is in horizontal position ready to be returned to inoperative 115 position by its springs and counter-weights 21 and 48 respectively.

120 When the parts have reached the position of Fig. 6, the next movement of the safety rudder will be back toward the inoperative position of Fig. 1. As the safety wing swings to inoperative position, the counter-weight 48 kicks the bell crank 87, releasing the latch 85 and permitting the spring 84 to act against the spring 76. At 125 this time, all of the latches will be inoperative, and the position of the disc will be predetermined by the relative strengths of the springs 84 and 76. Preferably, the combined action of these springs will be to shift 130

the discs to the position indicated in dotted lines in Fig. 3, with consequent movement of the control lever to normal position. Obviously, this last movement of the levers could be used to cause either a slight climbing or slight gliding of the plane.

To recapitulate, the three automatic movements of the safety rudder are accompanied by three automatic movements of the tail 10 rudder. As the safety rudder swings to the vertical position of Fig. 5, the tail rudder swings upwardly to the climbing position of Fig. 5. As the safety rudder swings to the horizontal position of Fig. 6, the tail rudder 15 swings to the gliding position of Fig. 6, and as the safety rudder swings to the inoperative position of Fig. 1, the tail rudder swings to its normal neutral position, or to either a slight gliding or climbing angle, as may be 20 desired, and as may be predetermined by the relative strengths of the springs 84 and 76.

An extremely simple form of mechanism has been shown for automatically resetting 25 the levers 66, 67, and their associated mechanism. The resetting device is in the nature of a lever 90 to which is pivoted a short link 91 connected by toggle levers 92, 93 to the upper end of lever 66 and the lower end 30 of lever 67 respectively. As the resetting lever is moved rearwardly, the lower ends of the levers 66 and 67 will be separated until they engage their latches 69. The disc 74 will be carried with the lower end 35 of the lever 77 until it is engaged by its latch 78. The arm 83 will be carried by lever 66 to a position where it may be engaged by the latch 76, as soon as the counter-weight 48 moves off the bell crank.

40 In conclusion it is to be noted that the showing of the supplemental safety rudder mechanism, particularly in Figs. 5, 6 and 7 is quite diagrammatic, and that the specific type of automatic tail rudder control is 45 merely illustrative of one form of the invention. Obviously, numerous expedients might be resorted to for controlling the tail lever from the safety wing, and for restoring the safety wing to inoperative position after 50 it has served the purpose. In connection with the restoration of the safety wing, I also contemplate the use of a vacuum tank in the event that the torsional springs and counter-weight prove too heavy or too cumbersome.

55 Various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

65 1. An aeroplane including a frame pivot-

ed to the body of the plane and normally held in inoperative position against said body, a safety rudder pivoted intermediate its ends in the frame, means for preventing pivotal movement of the rudder in the frame 70 as the rudder and frame swing upwardly and rearwardly on the frame pivot.

2. An aeroplane including a frame pivoted to the body of the plane and normally held in inoperative position against said body, 75 a safety rudder pivoted intermediate its ends in the frame, means for preventing pivotal movement of the rudder in the frame as the rudder and frame swing upwardly and rearwardly on the frame pivot, and means 80 for rendering said preventing means inoperative when the rudder and frame reach vertical position.

3. An aeroplane including a frame pivoted to the body of the plane and normally held 85 in inoperative position against said body, a safety rudder pivoted intermediate its ends in the frame, means for preventing pivotal movement of the rudder in the frame as the rudder and frame swing upwardly and rear- 90 wardly on the frame pivot, said means including a cross bar blocking swinging movement of the rudder.

4. An aeroplane including a frame pivoted to the body of the plane and normally held 95 in inoperative position against said body, a safety rudder pivoted intermediate its ends in the frame, means for preventing pivotal movement of the rudder in the frame as the rudder and frame swing upwardly 100 and rearwardly on the frame pivot, said means including a cross bar blocking swinging movement of the rudder, and gravitationally operable means for shifting the cross bar out of blocking position when the 105 frame and rudder reach vertical position.

5. An aeroplane including a frame pivoted to the body of the plane and normally held in inoperative position against said body, a safety rudder pivoted intermediate 110 its ends in the frame, means for preventing pivotal movement of the rudder in the frame as the rudder and frame swing upwardly and rearwardly on the frame pivot, said means including a cross bar blocking swinging movement of the rudder, and gravitationally operable means for shifting the cross bar out of blocking position when the frame and rudder reach vertical position, including arms slidably connected to the frame 115 and carrying the cross bar and counter-weighted arms pivotally connected to the frame and to said first mentioned arms.

6. An aeroplane including a frame pivoted to the body of the plane and normally held in inoperative position against said body, a safety rudder pivoted intermediate 125 its ends in the frame, means for preventing pivotal movement of the rudder in the frame as the rudder and frame swing upwardly 130

and rearwardly on the frame pivot, and means for rendering said preventing means inoperative when the rudder and frame reach vertical position, said rudder being pivoted near its upper end, whereby when it is released differential air pressures on its two ends will swing it to approximately horizontal position.

7. A device of the class set forth in claim 1, wherein gravity latches normally retain the rudder against upward swinging movement.

8. A device as set forth in claim 1, and wherein the rudder and its associated mechanism are normally disposed in a depression in the top of the body of the plane whereby they offer no air resistance when in inoperative position.

9. An aeroplane including a frame pivoted to the body of the plane and normally held in inoperative position against said body, a safety rudder pivoted intermediate its ends in the frame, means for preventing pivotal movement of the rudder in the frame as the rudder and frame swing upwardly and rearwardly on the frame pivot, means for rendering said preventing means inoperative when the rudder and frame reach vertical position, said rudder being pivoted near its upper end, whereby when it is released differential air pressures on its two ends will swing it to approximately horizontal position, and means acting on the frame to restore the latter to inoperative position when the rudder has swung to approximately horizontal position under the pressure of the air against it.

10. An aeroplane including a frame pivoted to the body of the plane and normally held in inoperative position against said body, a safety rudder pivoted intermediate its ends in the frame, means for preventing pivotal movement of the rudder in the frame as the rudder and frame swing upwardly and rearwardly on the frame pivot, and means for initiating upward swinging movement of the rudder and frame as the aeroplane dives at a dangerous angle.

11. An aeroplane including a frame pivoted to the body of the plane and normally held in inoperative position against said body, a safety rudder pivoted intermediate its ends in the frame, means for preventing pivotal movement of the rudder in the frame as the rudder and frame swing upwardly and rearwardly on the frame pivot, and means for initiating upward swinging movement of the rudder and frame as the aeroplane dives at a dangerous angle, said means including a flap secured to the rudder and automatic means lifting the flap.

12. An aeroplane including a frame pivoted to the body of the plane and normally held in inoperative position against said body, a safety rudder pivoted intermediate

its ends in the frame, means for preventing pivotal movement of the rudder in the frame as the rudder and frame swing upwardly and rearwardly on the frame pivot, and means for initiating upward swinging movement of the rudder and frame as the aeroplane dives at a dangerous angle, said means including a flap secured to the rudder and automatic means lifting the flap, including a gravity operated kicker mechanism.

13. A device of the class described in claim 1, and wherein a flap hingedly connected to the rudder is adapted to automatically swing to vertical position when the plane backsips.

14. In an aeroplane including a tail rudder formed with a pivoted section, a frame pivoted to the top of the body of the aeroplane, a safety rudder pivotally mounted in the frame and locked against pivotal movement therein, except when the frame is in approximately vertical position, said frame and the safety rudder being adapted to swing upwardly when the plane dives at a dangerous angle, and operative connections between the safety rudder and the pivoted section of the tail rudder.

15. In an aeroplane including a tail rudder formed with a pivoted section, a frame pivoted to the top of the body of the aeroplane, a safety rudder pivotally mounted in the frame and locked against pivotal movement therein, except when the frame is in approximately vertical position, said frame and the safety rudder being adapted to swing upwardly when the plane dives at a dangerous angle, and operative connections between the safety rudder and the pivoted section of the tail rudder, to swing the tail rudder section to climbing position as the safety rudder swings toward vertical position.

16. In an aeroplane including a tail rudder formed with a pivoted section, a frame pivoted to the top of the body of the aeroplane, a safety rudder pivotally mounted in the frame and locked against pivotal movement therein, except when the frame is in approximately vertical position, said frame and the safety rudder being adapted to swing upwardly when the plane dives at a dangerous angle, and operative connections between the safety rudder and the pivoted section of the tail rudder to swing the tail rudder section in climbing position as the safety rudder swings toward vertical position, said safety rudder being eccentrically pivoted in the frame and automatically released for free pivotal movement when the frame reaches vertical position, whereby the safety rudder will be swung to approximately horizontal position by the action of the wind.

17. In an aeroplane including a tail rudder formed with a pivoted section, a frame pivoted to the top of the body of the aero-

plane, a safety rudder pivotally mounted in the frame and locked against pivotal movement therein, except when the frame is in approximately vertical position, said frame and the safety rudder being adapted to swing upwardly when the plane dives at a dangerous angle, and operative connections between the safety rudder and the pivoted section of the tail rudder to swing the tail rudder section in climbing position, as the safety rudder swings toward vertical position, said safety rudder being eccentrically

pivoted in the frame and automatically released for free pivotal movement when the frame reaches vertical position, whereby the safety rudder will be swung to approximately horizontal position by the action of the wind, and operative connections between the safety rudder and tail rudder section for swinging the tail rudder section to gliding position as the safety rudder swings to horizontal position. 15 20

LUDWIG MARSCHALL.
